TRAVELING-WAVE TUBE

Stanley E. Webber, Ballston Lake, N. Y., assignor to General Electric Company, a corporation of New York

Application June 29, 1950, Serial No. 171,178

5 Claims. (Cl. 315—3.5)

This invention relates to improvements in electron discharge devices of the type generally called traveling-wave tubes; and its principal object is to increase the maximum power output, the gain, and the efficiency of such tubes, especially for use as power amplifiers. Other objects and advantages will appear as the description proceeds.

The features of this invention which are believed to be novel and patentable are pointed out in the claims which form a part of this specification. For a better understanding of the invention, reference is made in the following description to the accompanying drawing, in which Fig. 1 is a schematic longitudinal section of a traveling-wave tube embodying principles of this invention; Fig. 2 is a fragmentary side view of the same tube showing details of the attenuator construction; and Fig. 3 is a fragmentary longitudinal section of a modification of the improved traveling-wave tube.

Referring now to Fig. 1 of the drawing, the traveling-wave tube amplifies an electromagnetic wave transmitted between input terminal 1 and output terminal 2. Connecting these terminals is a structure which transmits electromagnetic waves at relatively low velocity. This structure may be an electrically conductive wire helix 3, as shown in the drawing. Since an electromagnetic wave travels along the wire of helix 3 at substantially the speed of light, the velocity of the wave along the axial direction of the helix is less than the speed of light by a factor substantially proportional to the ratio between the pitch of helix 3 and its diameter. It is known in the art that other structures which transmit electromagnetic waves at relatively low velocity may be used in place of the helix, and it will be understood that such other structures may be used in the practice of my invention. Examples of structures which have been proposed for such use are a rod which is electrically "loaded" with a plurality of rather closely spaced transverse metal disks, or a cylindrical wave guide loaded with a plurality of apertured disks. Connection of terminals 1 and 2 to external circuits may be made by direct connections to the wire, or by inductive or capacitative coupling, e. g., by a probe, cavity or wave-guide connection, as is known in the art.

Closely surrounding and enclosing helix 3 is a tubular envelope 4 which is usually made of electrically nonconductive material, such as glass. This envelope is evacuated in the customary manner. An alternative structure is one in which the evacuated envelope is a metal cylinder at some distance outside the helix, within which the helix is supported by insulating rods.

Within the left-hand end of envelope 4 there is an electron gun comprising a cathode 5, a cathode heater 6, and a focusing electrode 7. Electrode 7 may be tubular in shape, so that a beam of electrons, indicated by dotted lines 8, is directed axially through helix 3 to a collector plate 9 positioned within the right-hand end of envelope 4. Means, not shown, may be provided to produce a longitudinal magnetic field through the envelope to keep

2

electron beam 8 in focus. It is known in the art that the electron gun structure may be modified, if desired, to insure a more uniform current density in the beam, or to provide a hollow electron beam so that maximum current density will occur very close to the wire of helix 3, where the field of the transmitted electromagnetic wave is strongest. A battery 10, or other suitable voltage source, is connected to maintain electrode 7 and collector plate 9 at a large positive potential with respect to cathode 5, and a battery 11, or other current source, is provided to supply operating current to heater 6.

The ratio of pitch to diameter of helix 3 and the electron accelerating potential provided by battery 10 are so related that electron beam 8 travels in the same direction and at near the same velocity as electromagnetic waves transmitted by helix 3 between the input terminal 1 and output terminal 2. The adjustment is such that the velocity of the electron beam is slightly greater than that of the wave type with which it is to react. Under these conditions, it is known that interaction between the beam and the wave occurs in such a way that the electromagnetic wave is amplified as it travels along the helix. One explanation of this interaction, by J. R. Pierce, may be found in The Bell System Technical Journal, vol. 29, No. 1 (January 1950), pp. 6-19.

Because the traveling-wave tube is capable of amplifying a very broad band of frequencies, it is difficult to match exactly the impedances of the connecting circuits at input terminal 1 and output terminal 2 to the impedance of the helix at all frequencies which the tube can amplify. Therefore, at certain frequencies there may be reflections whereby an amplified wave is reflected from the output back to the input, where it is reflected again and further amplified as it travels back toward the output. This may produce oscillations unless an attenuator is provided such that the attenuation of the wave in the backward direction exceeds the gain in the forward direction. Several ways of providing this attenuation have been suggested, such as making the helix itself of a lossy material. However, the most convenient way of providing the necessary attenuation is to provide an attenuator 12 of lossy, electrically conductive material about the outside, or the inside or as a part, of envelope 4. This attenuator may, for example, be a platinum band positioned about the outside of the envelope, or an Aquadag coating applied to the surface of the envelope. Since a portion of the field of the transmitted electromagnetic wave extends through the envelope, an attenuator so placed absorbs energy from the field, and can easily be made to provide the required attenuation. Some of the attenuators previously used extend substantially throughout the entire length of the helix. However, it has been found that a relatively short attenuator can be employed to greater advantage.

According to known prior art, the location of the attenuator along the helix was believed to be unimportant. When a short attenuator was employed, it was usually placed near the center of the helix. According to the present invention, however, the location of the attenuator has an important effect upon the maximum power output, gain, and efficiency of the tube, as will now be explained.

Best results can be obtained by placing attenuator 12 near the input terminal of the helix, as shown in Fig. 1, rather than near the center of the helix as in previous practice. It has been found that maximum power output from the tube can be obtained when attenuator 12 is placed as close as possible to input terminal 1, and that the maximum output power decreases as the attenuator is moved toward the output terminal 2. A possible explanation of this fact is that the electromagnetic wave transmitted by the helix is weakest near the input terminal, since the wave is amplified as it travels along the

helix. Therefore, for a given percentage attenuation of the wave, less power is absorbed when the attenuator is immediately adjacent the input terminal, as shown in Fig. 3. If high gain is unimportant, this is the optimum location of the attenuator.

However, the maximum power location of the attenuator does not provide maximum gain from the tube. I have found that maximum gain is obtained when the attenuator is spaced a short distance from the input terminal, as shown in Fig. 1. However, since the attenuator is still relatively close to the input terminal, the maximum power output obtainable is not far below the optimum value. Therefore, by placing the attenuator for maximum gain, the maximum power output is also increased over that obtainable with previous arrangements, and is very near the optimum value. The efficiency of the tube is also increased, since more power output is obtained without increasing the input power supplied to the electron beam. This is an especially important advantage when the traveling-wave tube is to be used as a power amplifier, since, previously, a serious objection to traveling-wave tubes for such use has been their relatively low efficiency.

The optimum spacing for maximum gain between input terminal 1 and attenuator 12 is in the order of one wavelength of the electromagnetic wave as transmitted by helix 3. Since the traveling-wave tube is an extremely broad-band device, this distance, expressed in wavelengths, may vary considerably, even for the same tube when transmitting different wavelengths. A spacing as small as one-half wavelength, or as large as two wavelengths of the transmitted wave may give good results. However, in all cases the position of the attenuator is relatively close to input terminal 1, since the total length of the helix in an efficient traveling-wave tube may be seven or more wavelengths of the electromagnetic wave as transmitted by the helix.

The attenuator itself should be as short as it can be made while still providing a sufficient amount of attenuation to prevent oscillations. In a practical tube, the spacing between input terminal 1 and the attenuator may be in the order of 20%, or less, of the helix length, while the spacing between the attenuator and output terminal 2 may be in the order of 60%, or more, of the helix length. Thus, the latter spacing is much greater than the former.

A possible explanation of the increased gain obtained by placing the attenuator a short distance from the input terminal follows: In the space between the input terminal and the attenuator, the electron beam is velocity modulated to some extent by the electromagnetic wave transmitted by the helix. This is especially true when the signal is relatively large, as in power amplifier applications of the tube. That portion of the helix adjacent the attenuator then acts as a drift space in which electron bunching takes place. The bunched electrons induce an electromagnetic wave in that portion of the helix between the attenuator and output terminal 2, thereby providing considerable amplification of the transmitted wave. If the attenuator is placed as close as possible to input terminal 1, the immediate attenuation of the input signal reduces this velocity modulation of the beam by an amount which depends upon the rate of attenuation, and therefore the gain obtained from bunching of the electrons is reduced. The wave can be attenuated so fast that there is no velocity modulation of the beam. On the other hand, the necessary velocity modulation occurs within a relatively short distance, in the order of one wavelength of the transmitted wave, and any additional spacing between the input terminal and the attenuator produces no useful result, but actually reduces the gain, as well as the maximum output power and efficiency.

To prevent successive reflections between the output terminal and the right-hand edge of the attenuator, which could produce undesired oscillations, the right-hand edge

of the attenuator is preferably serrated, as shown in Fig. 2, so that there is no abrupt impedance discontinuity to create reflections at the right-hand edge of the attenuator.

Traveling-wave tubes embodying this invention may be used either as amplifiers or as oscillators, depending upon the external circuit employed with the tube. When used in an oscillator, a positive feedback circuit is provided between the output and input terminals. Since the tube does not oscillate in itself, the frequency of oscillation can easily and accurately be controlled by the feedback circuit.

It should be understood that the theoretical explanations given in this specification are for clarity only, and that applicant's invention is not limited to any particular theory of operation of the traveling-wave tube.

Having described the principle of this invention, and the best mode in which I have contemplated applying that principle, I wish it to be understood that the apparatus described is illustrative only, and that other means can be employed without departing from the true scope of the invention.

What I claim as new and desire to secure by Letters Patent of the United States is:

1. An electron discharge device comprising a transmission structure having input and output terminals between which electromagnetic waves are transmitted at low velocity, means providing an electron beam in proximity to said structure traveling in the same direction and at near the same velocity as an electromagnetic wave so transmitted, whereby interaction between said beam and said wave occurs to amplify the wave, and attenuator means placed in proximity to said structure within the field of electromagnetic waves transmitted thereby having a length substantially less than half that of said transmission structure, characterized in that said attenuator is spaced from the input terminal of said structure a distance not exceeding two wavelengths of the electromagnetic wave as transmitted by said structure and is spaced from the output terminal of said structure by a much greater distance, said attenuator means being the only attenuating means in proximity to said transmission structure between the input and output terminals thereof so that substantially more attenuation is present in the input half of said transmission structure than in the output half of said transmission structure.

2. An electron discharge device comprising a transmission structure having input and output terminals between which electromagnetic waves are transmitted at low velocity, means providing an electron beam in proximity to said structure traveling in the same direction and at near the same velocity as an electromagnetic wave so transmitted, whereby interaction between said beam and said wave occurs to amplify the wave, and attenuator means placed in proximity to said structure within the field of electromagnetic waves transmitted thereby, the length of said attenuator being substantially less than half the length of said structure, characterized in that said attenuator is spaced from the input terminal of said structure a distance not exceeding one-fifth the total length of said structure and from said output terminal a distance exceeding $\frac{3}{5}$ the total length of said transmission structure, said attenuator means being the only attenuating means in proximity to said transmission structure between the input and output terminals thereof so that substantially more attenuation is present in the input half of said transmission structure than in the output half of said transmission structure.

3. An electron discharge device comprising a transmission structure having input and output terminals between which electromagnetic waves are transmitted at low velocity, means providing an electron beam in proximity to said structure traveling in the same direction and at near the same velocity as an electromagnetic wave so transmitted, whereby interaction between said beam and said wave occurs to amplify the wave, and

attenuator means placed in proximity to said structure within the field of electromagnetic waves transmitted thereby, the length of said attenuator being short compared to the length of said structure, characterized in that said attenuator is spaced from the input terminal of said structure a distance in the order of one wavelength of the electromagnetic wave as transmitted by said structure, said attenuator also having a gradually decreasing volume toward the edge thereof nearer said output terminal to eliminate abrupt impedance discontinuity, said attenuator means being the only attenuating means in proximity to said transmission structure between the input and output terminals thereof so that substantially more attenuation is present in the input half of said transmission structure than in the output half of said transmission structure.

4. A traveling-wave tube comprising input and output terminals, a long, electrically conductive helix connected between said terminals for transmitting electromagnetic waves therebetween at low velocity, an electrically non-conductive, tubular, evacuated envelope closely surrounding and enclosing said helix, means providing an electron beam axially through said helix, said last-named means comprising an electron gun within one end of said tubular envelope and a collector plate within the other end of said envelope, a cylindrical attenuator of lossy, electrically conductive material about said envelope and within the field of electromagnetic waves transmitted by said helix, said attenuator being short compared to the length of said helix, said attenuator being spaced from said input terminal a distance not exceeding one-fifth the length of said helix, the edge of said attenuator nearest said output terminal being serrated to prevent the occurrence of an abrupt impedance discontinuity which

might produce reflections, said cylindrical attenuator being the only attenuator associated with said helix so that substantially more attenuation is present in the half of said helix adjacent said input terminal than is present in the half of said helix adjacent said output terminal.

5. An electron discharge device comprising a transmission structure having input and output terminals between which electromagnetic waves are transmitted at low velocity, means providing an electron beam in proximity to said structure traveling in the same direction and at near the same velocity as an electromagnetic wave so transmitted, whereby interaction between said beam and said wave occurs to amplify the wave, and a single cylindrical attenuator placed in proximity to 10 and surrounding said structure within the field of electromagnetic waves transmitted thereby, the length of said attenuator being short compared to the length of said structure, characterized in that said attenuator is placed immediately adjacent said input terminal said cylindrical attenuator being the only attenuator associated with said transmission structure so that substantially more attenuation is present in the half of the 15 transmission structure adjacent said input terminal than is present in the half of said transmission structure adjacent said output terminal.
